UNITED STATES PATENT OFFICE

121,441

DESIGN FOR A GRAND PIANO

William Zaiser, Rockville Centre, N. Y.

Application April 4, 1940, Serial No. 91,467

Term of patent 7 years

To all whom it may concern:

Be it known that I, William Zaiser, a citizen of the United States, residing at Rockville Centre, in the county of Nassau and State of New York, have invented a new, original and ornamental Design for a Grand Piano, of which the following is a specification, reference being had to the accompanying drawing, forming part thereof.

In the drawing: Fig. 1 is a perspective view of a grand piano, showing my new design, the side not shown being the same as to surface appearance as the side shown; and Fig. 2 is a top plan view thereof.

The dotted lines indicate a grilled opening in the cover of the pianos.

I claim:

The ornamental design for a grand piano, as shown and described

WILLIAM ZAISER.
